UNITED STATES PATENT OFFICE.

PAUL SWENSON, OF HOPKINS, MINNESOTA.

HEATER FOR GASEOUS FLUIDS.

1,133,825.

Specification of Letters Patent. Patented Mar. 30, 1915.

Application filed January 23, 1914. Serial No. 313,803.

To all whom it may concern:

Be it known that I, PAUL SWENSON, a citizen of the United States, residing at Hopkins, in the county of Hennepin and State of Minnesota, have invented certain new and useful Improvements in Heaters for Gaseous Fluids; and I do hereby declare the following to be a full, clear, and exact description of the invention, such as will enable others skilled in the art to which it appertains to make and use the same.

My invention has for its object to provide an improved heater or vaporizer for explosive engines, and more particularly, a heater or vaporizer that vaporizes the heavier hydro-carbon liquids, such as kerosene, as well as the lighter or more volatile hydro-carbons such as gasoline.

Generally stated, the invention consists of the novel devices and combinations of devices hereinafter described and defined in the claims.

In the accompanying drawings which illustrate the invention, like characters indicate like parts throughout the several views.

Referring to the drawings: Figure 1 is a side elevation showing the complete heater; Fig. 2 is a vertical section taken approximately on the line $x^2 x^2$ on Fig. 1, some parts being shown in full; and Fig. 3 is a section taken on the line $x^3 x^3$ on Fig. 2.

The carbureter casing is, as shown, made up of three sections, to-wit, a lower oil reservoir 1, an upper shell 2 affording what is designated as a mixing chamber, and an intermediate shell 3 affording what is designated as a vaporizing conduit 3'. The oil reservoir 1 may be of the usual or any suitable construction, and the same statement is true in respect to the mixing chamber 2. The oil reservoir 1 receives oil from an oil supply pipe 4 and delivers the same through an opening 5 into the lower portion of the vaporizing conduit 3', under the action of suction and the control of valve mechanism of well known or any suitable construction, forming no part of the present invention, and hence, not necessary for the purpose of this case to consider. It may be noted, however, that the said oil reservoir 1 has a supplemental air intake pipe 6, through which sufficient air is drawn to carry upward with it the volatile oil or hydro-carbon contained in the oil well.

The mixing chamber 2, at its ends marked 2² is adapted for connection to the manifold

or to the explosion chamber of an explosive engine, and it is provided with an auxiliary air intake port at 7, normally closed by a main air intake valve 8 of any suitable construction, not necessary for the purposes of this case to consider.

One or more exhaust flues, preferably several, and as shown, 2 such flues, indicated by the numeral 9, are passed transversely through the vaporizing conduit 3'. These flues are preferably made of brass and at one end are provided with stop flanges 10, and at their other ends with annular nuts 11. These flanges 10 and nuts 11 clamp the outer faces of the opposite walls of the vaporizing conduit 3' and securely hold the said flues in position and have tight joints between the flues and the walls of the said chamber. The external surfaces of these flues are formed with circumferentially extended annular grooves that are preferably V-shaped in cross section like the threads of a screw. The said grooves 12 are shown as helical. The vaporizing conduit 3' is internally formed with cylindrical surfaces 13 that engage the sharp projecting edges of the ribs or threads formed by the grooves 12, and co-operating therewith to afford a multiplicity of closely positioned and comparatively small channels, through which the air and volatile and more or less vaporized hydro-carbon are drawn on their way from the oil reservoir 1 to the so-called mixing chamber 2. The upper and lower internal cylindrical surfaces of the said conduit 3' are connected by a port 14 that extends parallel to the axes of the flues 9 from one wall to the other of the vaporizing conduit. The lower portion of the lower internal cylindrical surfaces of the said vaporizing conduit 3' is connected to the intake passage 5, by a port 15 similar to the port 14; and in like manner, the upper portion of the upper internal cylindrical surface of said conduit 3' is in communication with the mixing chamber 2 through a port 16, which, like the said ports 14 and 15, extends from one side to the other of the vaporizing conduit.

In this improved vaporizer, I utilize the heat from the exhaust of the explosive engine, as a medium for heating the volatile hydro-carbon and primary charge of air, so as to thereby increase the volatility of the hydro-carbon and the absorbing property of the air, and this is accomplished by direct-

ing the exhaust through the exhaust flues 9. To such ends, a hood 17 is securely fastened on one side of the shell or casing 3, so as to afford a passage 18 between the adjacent 5 ends of the flues 9; and to the other side of the said shell 3 I secure a divided hood 19 formed with internal chambers 20 and 21. The upper chamber 20, through a neck 22 and other connections, not shown, receives 10 the exhaust from the explosive engine and directs the same through the upper flue 9, from whence the exhaust products of combustion are directed downward through the passage 18, thence, through the lower flue 9 15 into the lower chamber 21 and from thence outward, through the opening 23 and other connections if desired, either to a muffler, or directly to the atmosphere. As is evident, the exhaust will keep the flues 9 and the 20 walls of the vaporizing conduit at such temperature that heavy oils, such as kerosene, will be rendered very volatile, and hence, the air drawn in therewith, and also heated, will absorb and carry with it in vapor form, 25 sufficient hydro-carbon to afford the proper explosive mixture when further reduced in richness by mixture therewith of the air drawn into the mixing chamber 2 through the auxiliary air intake port 7. The vaporizing action is very materially increased by 30 a plurality of capillary or very small passages through which the air and volatile vapor are drawn and which are formed by the threads or grooves in the peripheries of 35 the flues 9. Otherwise stated, a very large number of small streams of volatilized hydro-carbon and air are directed against the hot surfaces of the flues. Also, the thread-like grooves prevent a central convergence 40 of the vapor as it is drawn upward through the vaporizing chamber.

The peripheral corrugations and intervening grooves formed on the outer surface of the flues 9, as is obvious, very greatly increase 45 the outer radiating surface exposed for contact with the hydro-carbon vapors and air. From a broad point of view, however, the invention consists in providing a

multiplicity of relatively small passages in the vaporizing conduit between the walls 50 thereof and the outer surface of the exhaust flue or flues. The flues 9 can be removed for cleaning purposes.

The heater or vaporizer described is of simple construction and comparatively small 55 cost, and has no parts liable to get out of order, and has no delicate joints, such as formed between small flues and flue sheets, and which joints are liable to be burned out or destroyed and rendered leaky by the hot 60 products of exhaust.

What I claim is:

1. In a heater for heating one gaseous fluid from another, the combination with a casing formed with internal cylindrical surfaces and diametrically opposite inlet and outlet ports, of a flue extended through said vaporizing conduit and provided with closely adjacent external ribs extended in a circumferential direction around the same and 70 closely following the cylindrical surfaces of the said conduit and coöperating therewith to afford a multiplicity of small segmental passages surrounding said flue.

2. In a heater for heating one gaseous 75 fluid from another, the combination with a casing having a vaporizing conduit formed with internal cylindrical surfaces located at different points in said conduit, flues extended axially through the cylindrical portions 80 of said conduit, the said flues having closely adjacent external extensions in a circumferential direction allowing the same to closely follow the adjacent cylindrical surfaces of the said conduit and coöperating 85 therewith to afford a multiplicity of small segmental passages surrounding said flue, and a hood connecting the said flues at one end.

In testimony whereof I affix my signature 90 in presence of two witnesses.

PAUL SWENSON.
